UNITED STATES PATENT OFFICE.

EDWIN J. YOUNG, OF WADSWORTH, OHIO.

HEATER ATTACHMENT FOR LOCOMOTIVE-INJECTORS.

SPECIFICATION forming part of Letters Patent No. 689,943, dated December 31, 1901.

Application filed September 27, 1901. Serial No. 76,769. (Model.)

To all whom it may concern:

Be it known that I, EDWIN J. YOUNG, a citizen of the United States, residing at Wadsworth, in the county of Medina and State of Ohio, have invented a certain new and useful Improvement in Heater Attachments for Locomotive-Injectors, of which the following is a full, clear, and exact description.

The object of this invention is to so modify the construction and operation of a hot-water injector, particularly one for use on a locomotive, that the steam may be diverted through the injector into the suction-pipe and thence into the tank in a volume sufficient to heat the water in the tank.

In carrying out my invention I provide for closing the injector-overflow when steam is admitted into the injector and controlling at the same time the steam-valves, so as to cause the steam to pass to the suction-pipe and tank, as above indicated.

The more perfectly to illustrate this invention, reference is made to my inventions in Patents No. 495,286, dated April 11, 1893, and No. 649,265, dated May 8, 1900, which show the general character of injectors to which it is applicable.

In carrying out my invention the overflow-valve is connected with the means for operating the main steam-valve and teaser, so as to insure the closing of the overflow as the main steam-valve is opened, and the said main steam-valve is provided with auxiliary operating mechanism whereby it may be given a further movement to admit steam into the injector, whence it passes to the suction-pipe and thence into the tank.

Having thus stated the principle of my invention, I will proceed now to describe the best mode in which I have contemplated applying that principle and then will particularly point out and distinctly claim the part, improvement, or combination which I claim as my invention.

In the accompanying drawings, illustrating my invention, in the several figures of which like parts are similarly designated, Figure 1 is a side elevation of one form of locomotive-injector to which my invention is applied. Fig. 2 is a vertical longitudinal section of the same. Fig. 3 is a side elevation, and Fig. 4 is an end elevation, of the auxiliary operat-

ing device for the main steam-valve with parts in position to inject water into the boiler; and Fig. 5 is a side elevation, and Fig. 6 is an end elevation, of the same parts in position when used as a heater. Fig. 7 is a longitudinal section of the parts of and as shown in Fig. 5.

I will proceed now to describe my invention, as illustrated in the drawings, as embodied in a hot-water injector for locomotives, but without thereby limiting my invention to this single application thereof, and expressly reserving the right to claim the invention wherever applicable. The casing 2 is of approved construction, having a steam-inlet 3, a suction-tube 4, an overflow 5, and a boiler connection 6. Other parts that are as usual and substantially such as shown in the patents referred to are the compound steam-valve 7 and teaser 8 and their respective seats, the steam-valve stem 9, the forcing-tube 10, the vertically - reciprocating overflow-valve 11, the check-valve 12 in the boiler connection, the steam-valve 13, operating in conjunction with the steam-jet 14 next the suction-tube, and the lifting-tube 15, with appropriate fluid-passages.

The main steam-valve 7 has its stem 9 connected by a yoke 16 with a lever 17, having a pivoted fulcrum-piece 18, and this lever is also connected by links 19, pivoted fulcrum 20, and links 21 with the stem of the overflow-valve 11, so that the operating mechanism of the steam-valve also actuates the overflow-valve. The stem 9 is provided at its outer end with a handle 22, having a screw-socket 23, whereby it is applied to the stem, and upon this socket-piece 23 is mounted a sleeve 24, having opposite L-shaped slots 25 and also a stop-notch 26. The sleeve has its position upon the socket-piece, and consequently upon the stem, relatively fixed by means of a nut or other abutment 27 next the injector-casing and by means of the engagement of the handle 22 with the outer end of said sleeve and its notched stop and the inner angular end of the slots 25 in said sleeve, so that in either position the movement of the sleeve by means of the valve-operating mechanism, including the lever 17, will be transmitted to the stem, and consequently to the steam-valve.

The stem 9 is swiveled to the steam-valve, and the sleeve 24 is rigidly connected with

the yoke 16, so that the said stem may have movements in the direction of its length independent of the movements imparted to it by the yoke 16 and lever 17, and this independent movement is effected by engaging the handle 22 and pulling it outwardly until it engages the notched stop at the outer end of the sleeve or by giving it a partial turn, so as to slip into the slots of the sleeve, the respective positions being illustrated in Figs. 3, 4, 5, and 6.

The operation is as follows: To start the injector, the lever is pulled back or to the left, Fig. 1, a short distance, and the main steam-valve 7 is thereby raised slightly from its seat and sufficient to admit steam to the teaser 8, whereby water is lifted, and then the lever 17 is pulled back its full stroke and steam is admitted to the injector, and simultaneously the overflow-valve is closed, and the handle 22 is in the position shown in Figs. 1, 3, and 4. Water will now pass to the boiler. If it be desired to heat the water in the tank, then the handle 22 is turned until it is in alignment with the slots 25, and then it is pushed into these slots and locked in their angles, as in Figs. 5, 6, and 7, and this movement of the handle serves to push in the valve-stem 9 a distance sufficient to cut off a full flow of steam and yet admit steam to the teaser, and since the overflow is closed the steam thus admitted in a small quantity passes to the suction-tube and thence to the tank, and so heats the water in the tank. In other words, by means of the attachment illustrated in detail in Figs. 3 to 6 it is possible to change the distance between the overflow and the main steam-valve and teaser, so that the main valve is raised from its seat to admit steam to the teaser, but not sufficiently to unseat the teaser, and at the same time the overflow being closed the steam passing through the valve or teaser will not escape at the overflow, but will pass down the suction pipe or tube into the tank. Thus the teaser admits just steam enough to answer the purpose of a heater, while the full flow of steam would be too much.

What I claim is—

1. In a steam water-lifting apparatus, such as an injector, a main steam-valve, an auxiliary steam-valve or teaser, an overflow-valve, primary operating means common to all, and a supplemental actuating mechanism comprising a relatively fixed slotted sleeve, and a coacting handle connected with the stem of

the main steam-valve and adapted to actuate said valve independently of the primary operating means, to decrease the flow of steam without affecting the position of the auxiliary steam-valve and the overflow, thereby to divert the steam to the water-supply to heat the water therein.

2. In an injector, a suction-tube, an overflow-valve, a main steam-valve and its teaser, primary operating means common to the steam-valves and overflow-valve, and an attachment for independently actuating the main steam-valve without affecting the positions of the teaser and overflow-valve, and comprising essentially a relatively fixed slotted sleeve applied to the primary operating means and a handle applied to the stem of the main steam-valve whereby said valve may be adjusted with relation to said relatively fixed sleeve to change the relation of the main steam-valve to its seat.

3. In an injector, a steam-valve, comprising a main valve and a teaser, an overflow-valve, actuating mechanism for these valves, and an independent operating device for the main valve, comprising a relatively fixed sleeve provided with L-shaped slots and a stop-notch, and a handle on the main-valve stem movable with relation to the said sleeve, and adapted to be fixed relatively thereto in either of two positions, so as to adjust the main steam-valve to admit a full flow of steam for supplying the boiler with water, and to reduce the supply of steam and divert it to the water-supply.

4. In an injector, a steam-valve, actuating mechanism therefor including a stem, provided with an abutment, such as a nut, a sleeve mounted upon the said stem and against such abutment and fixed relatively to the valve-actuating mechanism, the stem being capable of being turned within the said sleeve and provided with a transverse handle adjacent the outer end of the sleeve, and the said sleeve having a stop-notch and also longitudinal slots with which the said handle co-operates.

In testimony whereof I have hereunto set my hand this 24th day of September, A. D. 1901.

EDWIN J. YOUNG.
